UNITED STATES PATENT OFFICE

HARRY A. KNOX, OF DAVENPORT, IOWA

ENDLESS TRACK FOR TRACKLAVING VEHICLES

Original application filed August 8, 1924, Serial No. 730,947. Divided and this application filed October 6, 1925. Serial No. 60,873.

(Granted under the act of March 3, 1883, as amended April 30, 1928; 370 O. G. 757.)

The invention described herein, if patented, may be manufactured and used by or for the Government for governmental purposes without the payment to me of any 5 royalty thereon.

This invention relates to an endless track for track laying vehicles and is a division of co-pending application, Ser. No. 730,947, filed August 8, 1924.

10 In vehicles of the track laying type the weight of the vehicle is supported on trucks which carry wheels or rollers riding on a continuous rail formed on the inner side of an endless flexible track. When the track 15 consists of interlocking links joined by hinged pins the excessive strain of a vehicle of this character necessitates constant lubrication of the moving joints and frequent renewal of the elements of the track. With regard 20 to endless band tracks of non-metallic compositions their short duration renders installation nonfeasible.

The object of the present invention is to provide a flexible metallic band track of maximum strength and minimum weight, presenting a broad rail surface adaptable to the use of rubber or fabric covered rollers, sprocket and idler, and made of a plurality of component bands formed by a series of 25 overlapping plates and the bands connected and held together by driving lugs whose mode of attachment serves also to bind the plates together and to retain the customary shoes in place. According to this construction, a wide track may be built up and the shoes which extend beyond the meeting edge of the component bands may be of short 30 length and consequently less liable to break.

To these and other ends, my invention consists in the construction, arrangement, and combination of elements described hereinafter and pointed out in the claims forming a part of this specification.

40 A practical embodiment of the invention is illustrated in the accompanying drawings, wherein:

Fig. 1 is an inside plan view of a section of my improved metallic band track;

50 Fig. 2 is a view in side elevation thereof;

Fig. 3 is a sectional view on the line 3—3 of Fig. 1; and

Fig. 4 is an inside plan view of a track made up of three bands.

Referring to the drawings by numerals of reference:

The endless track is made up of a plurality of metallic bands 5 placed side by side and connected in a special manner, as will be described hereinafter. The bands, which are 60 identical, consist of a series of overlapping spring steel plates 6 preferably arranged in unit groups of three, the ends of an upper and a lower plate of each unit group overlapping 65 each other at the center of each intermediate plate. This arrangement provides at regular intervals a thickness of three plates approximately one-third the area of the band for the purpose of obtaining strength when assembled while a greater area of only two 70 thicknesses is obtained for providing flexibility.

Attached to the outer side of the bands at the points of strength are shoes 7 which serve in addition to their normal function, as a rib 75 for the connecting plates. The shoes are formed with a smooth tread and cover a sufficient area so that it will not be necessary to remove them when the vehicle is to be driven over improved roads. The shoes are of 80 greater length than the width of the individual bands so that in uniting bands to form a track a portion of the shoe may extend beyond the meeting edge of the adjoining band and thus be secured to both bands to hold them 85 together. The securing means may consist of bolts 8 but preferably the heads of the bolts are united to form a driving lug 9 which spans the adjoining bands, a spacer 10 being used on the band which presents but two thicknesses. The shoes are further secured at one or more other points as indicated by the bolt 11. The bolts for securing the shoes form the sole means for uniting 90 the overlapping plates 6. When two or more bands are thus connected the shoes of adjoining bands will be staggered and by reason of 95 their proximity to each other the pressure on the plates will be slight.

The roller 12 may be equipped with a twin 100

tire to bridge the central driving lug 9 and be held to the track thereby or alternately the heads of the end bolts 11 may be formed into driving or guiding lugs especially when the track is made up of three bands.

5 While in the foregoing there has been illustrated and described such combination and arrangement of elements as constitute the preferred embodiment of my invention, it 10 is nevertheless desired to emphasize the fact that interpretation of the invention should only be conclusive when made in the light of the subjoined claims.

I claim:

- 13 1. An endless track for track laying vehicles embodying a plurality of parallel endless bands, each formed of overlapping metallic plates in series and constituting a rail for a vehicle supporting wheel, shoes mounted across each band in staggered relation to the shoes of an adjoining band and extending partially over an adjoining band, and driving lugs spanning adjoining edges of the bands and anchored through the bands to the shoes.
- 25 2. An endless track for track laying vehicles embodying a plurality of endless bands each formed of overlapping metallic plates in series, spaced shoes on each band and extending to an adjoining band, and means for 30 securing each shoe to two bands, said means also serving to unite the plates of each band and to hold the adjoining bands together.
- 35 3. An endless track for track laying vehicles embodying a plurality of endless bands each formed of overlapping metallic plates in series, spaced shoes on each band and extending to an adjoining band, and means for 35 securing each shoe to two bands, said means also serving to unite the plates of each band.
- 40 4. An endless track for track laying vehicles embodying a plurality of endless bands each formed of overlapping connected metallic plates in series, spaced shoes on each band and extending to an adjoining band, and 45 means for securing each shoe to two bands.
- 45 5. An endless track for track laying vehicles embodying a plurality of endless bands formed of overlapping connected metallic plates in series, shoes on each band and driving 50 lugs spanning adjoining plates for securing the shoes and for holding the bands together.
- 55 6. An endless track for track-laying vehicles embodying a plurality of endless metallic bands placed side by side, a shoe extending across each band and partially over an adjoining band, a driving lug spanning adjoining edges of the bands on the side opposite the shoes and means passing through 60 the bands for securing the driving lug to the shoe.

HARRY A. KNOX.
